Adjustable Wheel Shield for 15" to 20" Rims. Product listing [online]. ECS Tuning [retrieved on Oct. 18, 2017]. Retrieved from the Internet: <URL:https://www.ecstuning.com/b-zane-products/adjustable-wheel-shield-for-15-to-20-rims/ws1520-zan/>.

Primary Examiner — Sheryl L Lane*Assistant Examiner* — Calvin E Vansant(74) *Attorney, Agent, or Firm* — James G. Passé; Passé Intellectual Property, LLC(57) **CLAIM**

The ornamental design for a spray shield, as shown and described.

DESCRIPTION

FIG. 1 is a perspective top front right view of the spray shield, showing my new design;

FIG. 2 is a perspective top rear left view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken-lines indicate regions designated for automotive related decals and form no part of the claimed design.

1 Claim, 7 Drawing Sheets(56)
